UNITED STATES PATENT OFFICE.

JACK E. MESSENGER, OF DES MOINES, IOWA.

CHOKE LATCH.

Application filed January 29, 1925. Serial No. 5,543.

To all whom it may concern:

Be it known that I, JACK E. MESSENGER, a citizen of the United States, residing at Des Moines, in the county of Polk and State of Iowa, have invented a certain new and useful Choke Latch, of which the following is a specification.

The object of my invention is to provide a choke latch for securely holding the choker rod of an automobile carburetor control in any of its adjusted positions, the parts being of simple, durable and comparatively inexpensive construction.

More particularly, my invention relates to a choke latch especially adapted for use upon a Ford automobile construction, wherein the choke latch may be supported upon a fixed bearing member by extending thereover, and therearound wherein the choke 20 latch will be securely anchored without any additional means.

Still a further object is to provide a choke latch having a spring actuated movable member adapted to engage the choker rod for 25 maintaining it against accidental movement after being manually moved for adjusting the carburetor.

Still a further object is to provide an actuated movable member arranged with a 30 flanged edge which is curved to form an arc of a circle conforming to the arc of a circle in which the end of a choker rod moves, wherein the choker rod will be in engagement with the movable member during all 35 of its movement.

Still a further object is to provide a choke latch in combination with a choker rod and a bell crank lever assembly together with the bearing for the bell crank lever wherein 40 the choke latch will cooperate with the bell crank lever assembly in such manner that when the choke latch is installed by simply placing it over the bell crank lever assembly, it is ready for operation without further 45 manipulation or adjustment.

With these and other objects in view, my invention consists in the construction, arrangement and combination of the various parts of my device, whereby the objects contemplated are attained, as hereinafter more 50 fully set forth, pointed out in my claims, and illustrated in the accompanying drawings in which:

Figure 1 is a sectional view through a portion 55 of a dash of an automobile showing the choker rod and bell crank lever assembly

with my improved choke latch installed in operative position.

Figure 1^A is a view of a carburetor with the connecting rod shown in position where 60 it connects with the bell crank lever shown in Figure 1.

Figure 2 is a front view of the choke latch taken along line 2-2 of Figure 1.

Figure 3 is a detail, sectional view taken 65 on line 3-3 of Figure 1 showing the supporting means for the latch support.

Figure 4 is a perspective view of the choke latch support; and

Figure 5 is a perspective view of the movable member of the choke latch showing the notched flange for engagement with the choker rod. 70

In the accompanying drawings, I have used the reference numeral 10 to indicate the 75 ordinary instrument board of a Ford or other automobile through which is slidably mounted a choker rod 11.

The choker rod 11 extends through a dash 12 just rearwardly of the engine of the automobile. 80

The upper edge of the dash 12 is connected to the instrument board 10 by the cowl 13. The ordinary hood 14 of the automobile is shown in section in Figure 1 of the drawings. 85

The choker rod 11 is provided with a right angled extension 13 adapted to extend through an opening formed in a bell crank lever 14.

The bell crank lever 14 is mounted in a 90 bearing 15 which is formed of a pair of spaced flanges 16 connected together by a connecting web 17. The connecting web 17 is riveted to the dash 12 by means of the rivets or the like 18.

The outer corners between the connecting flange 17 and the spaced members 16 are curved, as at 19, so that my choke latch support may be securely held in position as will hereinafter be more fully set forth. 95

The lower end of the free end of the bell crank lever 14 is connected to a control rod 20, which is connected to a bell crank 21, which forms a part of the ordinary carburetor 22. 100

The adjustment of the carburetor 22 may be made by pushing the rod 11 longitudinally, thereby operating the bell crank lever 14.

In order to permit longitudinal movement, 110 and at the same time permit the inner end of the choker rod 11 to travel in an arc of

a circle, it is necessary to have a slot 23 in the dash 12.

The parts just described are of the ordinary standard equipment of a Ford type of automobile.

My improved choke latch includes a support A formed of a metal stamping so as to have a vertical flange 24 arranged with a notch 25, which is of sufficient width to receive the connecting members 17 of the bearing 15.

The notch 25 separates the flange 24 into two parts 26. The parts 26 are formed with a raised or upstruck bead 27 for reinforcing purposes.

The two members 26 rest on each side of the connecting members 17 and fit into the corners 19 in such manner as to cause the support A to be securely anchored on the bearing; without the use of any additional means.

Extending downwardly and forwardly inclined from the flange 24 is a shelf or support 28, which is spaced nearer one side of the flange 26 than the other so as to permit the bell crank lever 14 to be free to operate, without interfering with the support or shelf 28.

The shelf 28 is formed with a pair of openings 29 through which are extended guide pins 30 having their lower ends bent in opposite directions to form stops 31.

The guides 30 are formed of a movable member 32, which consists of a flat bottom having an upturned flange 33 on one edge.

The shelf 28 is formed with an upturned flange 34 on one side. The movable member 32 rests upon the shelf 28 and against the upturned flange 24.

Coil springs 35 are interposed between the bottom of the movable member 32 and the top of the shelf 28.

The stops 31 limit the amount of movement in one direction of the movable member 32 relative to the shelf 28.

The flange 33 on the movable member 32 has its periphery formed with a plurality of notches 36, all of which are arranged so as to form an arc of a circle with the pivot or center point being arranged the same as the pivot upon which the bell crank lever 14 operates.

The angle extension 13 on the choke rod 11 travels over the flange 33 and is designed to be selectively received in any of the notches 36 therein.

The springs 35 tend to cause the extension 13 to be frictionally held in any of the notches 36 against undesirable accidental movement.

One part of the bell crank lever 14 rests against the outer side of the flange 33, whereby the movable member is confined or retained between the upturned flange 34 and the bell crank lever 14.

The choke rod 11, when moved longitudinally for changing the adjustment of the carburetor will be held in any of its moved or adjusted positions by engagement of the movable member 32 with the choke rod 11. 70

My choke latch may be quickly and easily mounted upon the bearing 15 and when mounted thereon is in position to operate by its cooperation with the choke rod 11.

Some changes may be made in the construction and arrangement of the various parts of my invention, without departing from the real spirit and purpose of my invention, and it is my intention to cover by my claims, any modified forms of structure or use of mechanical equivalents, which may be reasonably included within their scope. 75 80

I claim as my invention:

1. A choke latch for carburetor choke rods comprising a support adjacent the choke rod, a movable member mounted upon the support, said movable member having a plurality of notches therein adapted to selectively receive the choke rod and means interposed between the support and the movable member for yieldingly causing the movable member to engage the choke rod as and for the purposes stated. 85 90

2. A choke latch for carburetor choke rods comprising a support adjacent the choke rod, a movable member mounted upon the support, an upturned flange on said movable member having a plurality of notches therein adapted to selectively receive the choke rod and means interposed between the support and the movable member for yieldingly causing the movable member to engage the choke rod as and for the purposes stated. 95 100

3. A choke latch for carburetor choke rods in combination with a choke rod having a right angled extension on one end, a bell crank lever having the extension connected therewith and a bearing for the bell crank lever, comprising a support mounted adjacent the bell crank lever, a movable member mounted upon the support, a flange on said movable member having its edge curved upon an arc of a circle with the pivot of the bell crank lever as a center, the edge of said flange being formed with a plurality of notches for receiving the extension of the choke rod and yielding means for forcing the movable member upwardly against the extension of the choke rod for retaining the choke rod in any of its positions with the extension thereof in any of said notches. 105 110 115 120

4. A choke latch for carburetor choke rods in combination with a choke rod having a right angled extension on one end, a bell crank lever having the extension connected therewith and bearing for the bell crank lever comprising a support mounted adjacent the bell crank lever, said support being bifurcated for extending over and on 125 130

- each side of the bearing for anchoring it thereon without additional means and means movably mounted upon said support for engaging the choker rod for retaining it in 5 any of its movable positions.
5. A choke latch for carburetor choker rods in combination with a choker rod having a right angled extension on one end, a bell crank lever having the extension connected therewith and a bearing for the bell crank lever, comprising a support mounted adjacent the bell crank lever, said support being bifurcated for extending over and on each side of the bearing for anchoring it thereon without additional means, and a spring actuated movable member mounted 70 on said support, a flange on said last member having notches in its edge adapted to receive the choker rods for maintaining the choker rod against accidental movement after it is manually moved into any one of 75 said notches.
9. A choke latch for carburetor choker rods in combination with a choker rod having a right angled extension on one end, a bell crank lever having the extension connected therewith and a bearing for the bell crank lever comprising a support mounted adjacent the bell crank lever, said support being bifurcated for extending over and on each side of the bearing for anchoring it thereon without additional means and a member mounted upon said support, springs interposed between said member and the support for yieldingly holding it in one 80 position, a flange on said last member having notches in its edge adapted to receive the choker rod, said flange being curved in an arc of a circle having as its center the pivot of the bell crank lever so that the 85 choker rod when moved will travel upon the edge of the flange as and for the purposes stated.
10. A choke latch for carburetor choker rods in combination with a choker rod having a right angled extension on one end, a bell crank lever having the extension connected therewith and a bearing for the bell crank lever, comprising a support mounted adjacent the bell crank lever, said support being bifurcated for extending over and on 90 each side of the bearing for anchoring it thereon without additional means and a spring actuated movable member mounted on said support adapted to yieldingly engage and retain the choker rod in any of its 95 positions.
11. A choke latch for carburetor choker rods in combination with a choker rod having a right angled extension on one end, a bell crank lever having the extension connected therewith and a bearing for the bell crank lever, comprising a support mounted adjacent the bell crank lever, said support being bifurcated for extending over and on each side of the bearing for anchoring it thereon without additional means, said support having a pair of openings therein, a movable member positioned above said support, guides on said last member and extended through said openings, springs on 100 said guides positioned between said support and said member, said movable member being yieldingly held in engagement with the choker rod as and for the purposes stated.
12. A choke latch for carburetor choker rods in combination with a choker rod having a right angled extension on one end, a bell crank lever having the extension connected therewith and a bearing for the bell crank lever, comprising a support mounted adjacent the bell crank lever, said support being bifurcated for extending over and on each side of the bearing for anchoring it 105 thereon without additional means, said support having a pair of openings therein, a movable member positioned above said support guides on said last member and extended through said openings, said guides being yieldingly held in engagement with the choker rod as and for the purposes stated.
13. A choke latch for carburetor choker rods in combination with a choker rod having a right angled extension on one end, a bell crank lever having the extension connected therewith and a bearing for the bell crank lever, comprising a support mounted adjacent the bell crank lever, said support being bifurcated for extending over and on each side of the bearing for anchoring it 110 thereon without additional means, said support having a pair of openings therein, a movable member positioned above said support guides on said last member and extended through said openings, said guides being yieldingly held in engagement with the choker rod as and for the purposes stated.
14. A choke latch for carburetor choker rods in combination with a choker rod having a right angled extension on one end, a bell crank lever having the extension connected therewith and a bearing for the bell crank lever, comprising a support mounted adjacent the bell crank lever, said support being bifurcated for extending over and on each side of the bearing for anchoring it 115 thereon without additional means, said support having a pair of openings therein, a movable member positioned above said support guides on said last member and extended through said openings, said guides being yieldingly held in engagement with the choker rod as and for the purposes stated.
15. A choke latch for carburetor choker rods in combination with a choker rod having a right angled extension on one end, a bell crank lever having the extension connected therewith and a bearing for the bell crank lever, comprising a support mounted adjacent the bell crank lever, said support being bifurcated for extending over and on each side of the bearing for anchoring it 120 thereon without additional means, said support having a pair of openings therein, a movable member positioned above said support guides on said last member and extended through said openings, said guides being yieldingly held in engagement with the choker rod as and for the purposes stated.
16. A choke latch for carburetor choker rods in combination with a choker rod having a right angled extension on one end, a bell crank lever having the extension connected therewith and a bearing for the bell crank lever, comprising a support mounted adjacent the bell crank lever, said support being bifurcated for extending over and on each side of the bearing for anchoring it 125 thereon without additional means, said support having a pair of openings therein, a movable member positioned above said support guides on said last member and extended through said openings, said guides being yieldingly held in engagement with the choker rod as and for the purposes stated.
17. A choke latch for carburetor choker rods in combination with a choker rod having a right angled extension on one end, a bell crank lever having the extension connected therewith and a bearing for the bell crank lever, comprising a support mounted adjacent the bell crank lever, said support being bifurcated for extending over and on each side of the bearing for anchoring it 130 thereon without additional means, said support having a pair of openings therein, a movable member positioned above said support guides on said last member and extended through said openings, said guides being yieldingly held in engagement with the choker rod as and for the purposes stated.

the limiting means between said support and said member, springs on said guides positioned between said support and said member, said movable member being yieldingly held in engagement with the choker rod as and for the purposes stated.

12. A choke latch for carburetor choker rods comprising a support, said support having a pair of openings therein, a movable member positioned above said support, guides on said last member and extended through said openings, springs on said guides positioned between said support and said member, said movable member being yieldingly held in engagement with the choker rod as and for the purposes stated.

13. A choke latch for carburetor choker rods comprising a support, said support having a pair of openings therein, a movable member positioned above said support, guides on said last member and extended through said opening, springs on said guides positioned between said support and said member, a notched edge on said member adapted to engage the choker rod for retaining it against accidental displacement.

14. A choke latch for carburetor choker

rods in combination with a choker rod having a right angled extension on one end, a bell crank lever having the extension connected therewith, and a bearing for the bell crank lever comprising a support mounted adjacent the bell crank lever, said support being bifurcated for extending over and one each side of the bearing for anchoring it thereon without additional means, and a spring actuated movable member mounted on said support adapted to yieldingly engage and retain the choker rod in any of its positions, a flange on said support adapted to rest against one side of said movable member whereby the movable member will be held between said flange on the support and the bell crank lever.

15. A choke latch for carburetor choker rods comprising a support adjacent the choker rod having a plurality of notches therein for selectively receiving a portion of the choker rod for holding it against accidental movement, said support being capable of yielding movement as and for the purposes stated.

Des Moines, Iowa, January 2, 1925.

JACK E. MESSENGER.
